E. C. RUTTENBERG

FINIAL

Filed Dec. 9, 1922

UNITED STATES PATENT OFFICE.

EDWARD C. RUTTENBERG, OF CHICAGO, ILLINOIS.

FINIAL.

Application filed December 9, 1922. Serial No. 605,930.

To all whom it may concern:

Be it known that I, EDWARD C. RUTTENBERG, a citizen of the United States, residing at Chicago, in the county of Cook and State 5 of Illinois, have invented new and useful improvements in Finials, of which the following is a specification.

This invention relates to finials or shade clamps, such as used on floor, table, or other 10 pedestal lamps, for holding the shade in place, and an object of the invention is to provide a finial which will not only serve to hold the shade rigidly in place but one which will add to the aesthetic value of the lamp.

Another object of this invention is to provide a finial or shade clamp in which a composition of metal is utilized in combination with glass, crystal or analogous material in 15 providing a practical artistic finial.

Another object of this invention is to provide a finial or shade clamp as specified which embodies a novel manner of connecting the crystal with the main body.

A feature of my invention is the novel 25 manner in which one end portion of the crystal is directly embedded in the ornamental body.

Other objects of the invention will appear in the following detailed description 30 taken in connection with the accompanying drawings wherein:—

Fig. 1 is a side elevation of the improved finial.

Fig. 2 is a longitudinal section through 35 the finial taken on the line 2—2 of Fig. 1.

Fig. 3 is a side elevation of the core and crystal of the finial.

Fig. 4 is a longitudinal section taken on 40 the line 4—4 of Fig. 3.

Fig. 5 is a cross section on the line 5—5 of Fig. 1.

Referring more particularly to the drawings, the improved finial or shade clamp, 45 comprises essentially, the body 1 and core 2.

The body 1 is made of any suitable plastic 50 composition and is molded first, in two halves in its artistic design, after which the molded halves are placed one on each side of the core 2 and secured to each other by any suitable type of adhesive, or by the adhesive proclivities contained in the composition matter itself.

The core 2 comprises a metal tube or 55 sleeve 3 which has its outer surface corrugated as shown at 4 to increase the surface area, and also to prevent accidental rotary

or slipping movement of the composition body 1 relative to the core after the composition body has been properly placed in position. The tube 3 is provided with an inwardly extending annular flange 5 which forms an abutment for limiting the threading of the finial upon the threaded tube (not shown) of the lamp pedestal. The portion of the tube 3 below the flange 5 is internally threaded as shown at 6. The crystal or jewel 7 may be of any desired shape, color or design, and it has a substantially cylindrical stem 8 formed upon its lower portion, which stem is inserted into the tube 70 3, as clearly shown in Fig. 4 of the drawings, and is cemented therein by any approved type of cement as shown at 9, which will adhere securely to the metal of the tube 3 and to the crystal of the jewel or crystal 75 7. Such cement is well known in the art.

It will be noted by particular reference to Figs. 1 and 2 of the drawings that the composition body 1 entirely encloses the cylindrical portion 8 of the jewel, and also entirely encloses the tube 3. When the two sections of which the body 1 are formed are connected, they form a single unit or homogeneous body or mask permitting the cut or artistic upper edge of the crystal or jewel to 80 be exhibited above the body.

In the foregoing description I set forth one method of constructing the finial from composition material but I wish it to be understood that the body may be constructed 85 of various materials and in fact may be formed in a die casting operation which uses composition material known as "white metal." In other words the main portion of the body 1 may be made in one piece with 90 the crystal 7 therein as illustrated.

It is, of course, to be understood that the invention may be constructed in other manners and the parts associated in different relations and, therefore, I do not desire to be 95 limited in any manner except as set forth in the claims hereunto appended.

Having thus described my invention what I claim is:—

1. As a new article of manufacture a 100 finial comprising an ornamental body, and an ornamental element having a portion thereof embedded in said body.

2. As a new article of manufacture, a 105 finial for pedestal lamps comprising a body 110 of composition material, and a crystal having a stem embedded in said body.

3. A finial for pedestal lamps, comprising a body of composition material, a tube embodied in said body, and a crystal carried by said tube and projecting out of said body. 7. In a finial for pedestal lamps, a metal tube, a crystal having a stem formed thereon, said stem extending into and cemented to said body, and a body of composition material mounted about said tube and the stem of said crystal. 25
6. 4. A finial for pedestal lamps, comprising a body of composition material, a tube embodied in said body and having a threaded portion at one end, and a crystal carried by said tube and projecting out of said body. 8. A finial comprising an ornamental body having screw threads formed in one end portion, and an ornamental element having a portion embedded in the other end portion of said body. 30
10. 5. A finial for pedestal lamps, comprising a body of composition material, a tube embodied in said body and having a threaded portion at one end, and a crystal carried by said tube and projecting out of said body, 9. A finial comprising an ornamental body, attaching means for one end of the body, and a glass ornamental member having a portion thereof embedded in the other end of said body. 35
15. said tube provided with an annular inwardly extending flange at the inner terminal of its threaded portion. 10. A finial comprising an ornamental body having a threaded recess in one end thereof, and a one piece ornamental element directly attached to said body. 40
20. 6. A finial for pedestal lamps, comprising a body of composition material, a tube embodied in said body and having a threaded portion at one end, and a crystal carried by said tube and projecting out of said body, the major portion of the outer surfaces of said tube being roughened. In testimony whereof I affix my signature. 45

EDWARD C. RUTTENBERG.
